UNITED STATES PATENT OFFICE.

HENRY ALFRED GSSELL, OF PARIS, FRANCE.

APPARATUS FOR DISCHARGING MATCHES.

1,102,498.

Specification of Letters Patent.

Patented July 7, 1914.

Application filed June 12, 1913. Serial No. 773,312.

To all whom it may concern:

Be it known that I, HENRY ALFRED GSSELL, a citizen of the Republic of Switzerland, residing at 118 Boulevard de Clichy, Paris, France, have invented new and useful Improvements in Apparatus for Discharging Matches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has for its object to provide an improved apparatus for filling the finished matches discharged or ejected from match making machines into collecting boxes.

The invention is illustrated by way of example in the accompanying drawings in which:

Figure 1 is a side elevation, showing the device for ejecting the matches from the carrier-bars. Fig. 2 is a section on line II—II of Fig. 1. Fig. 3 which is to be taken together with Fig. 1, on the right side thereof, is a side elevation, showing the means for filling the matches into the collecting boxes.

Fig. 4 is an end view of the same. Fig. 5 is a section on line V—V of Fig. 3 drawn on a larger scale. Figs. 6 to 8 are detail views.

The carrier-bars 1, which are charged with the dried matches 2 produced in a match making machine not shown of any suitable construction, are moved vertically downward in a well-known manner in front of the device for ejecting the matches from the carrier bars. This device comprises a bar 3 in the face of which are set a number of pins 4. The bar 3 is horizontally reciprocated toward and away from the carrier-bars 1 by means of cams 5 on a shaft 6. On this shaft there is secured a toothed wheel 7 which meshes with a toothed wheel 8 on the main shaft 9 which is rotated by any suitable means not shown on the drawings. The cams 5 act on rollers 10^a mounted on arms 10 which are mounted to turn in bearings 11 on the machine frame and are pivoted to rods 12 connected to the ejector bar 3.

Boxes 13 for conveying the matches to the filling apparatus proper, travel beneath and horizontally past the ejecting mechanism in the direction of the arrows. In the illus-

trated example, each traveling box 13 consists of three compartments or cells, which are separated from one another for their entire height by wedge shaped partitions 14. The boxes are provided at their lower parts or underside each with a T-shaped projection or lug 15 by means of which they are guided in suitable guides 16 provided on horizontally disposed channel irons 17. Wheels 18, 19 serve for moving the boxes 13 in the direction of the arrows and for turning them, whereat the boxes push one another forward. The wheel 19 also serves for lowering the boxes from the upper row into the lower row, and the wheel 18 for raising the boxes again into the upper row. Both wheels 18, 19 are intermittently and synchronously turned from the shaft 9. A bevel wheel 20 on this shaft meshes with a bevel wheel 21 on a short shaft 22 on which there is secured a feed gear wheel 23 which meshes with a feed wheel 24 secured to the axle 25 of the wheel 18. The wheel 19 is turned by a similar mechanism not shown on the drawing, so that both wheels 18, 19 are simultaneously turned the same amount. The wheels are provided on their periphery with grooves 26, each of which is adapted to receive a box 13. Shields 27, 28 prevent the boxes from falling down from the wheels 18, 19.

By means of the mechanism described the boxes 13 are caused to move past two vertical rows A, B of collecting receptacles 29, 30, 31. For moving the collecting receptacles vertically downward there are arranged for each row A, B two endless chains 32, 33 and 34, 35 which pass on chain wheels 36 mounted on shafts 37, 38. An intermittent motion of rotation is imparted to the shaft 37 by means of a cam 39 mounted on a shaft 40 which is rotated from the main shaft 9 by means of a chain drive 41. The cam 39 acts on a roller 42^a mounted on a rod 42 the upper end of which is pivoted to an arm 43 mounted free to rock about the shaft 37. The arm 43 carries a pawl 44 which is adapted to engage a ratchet wheel 45 secured to the shaft 37. The two chains 32, 33 and 34, 35 of each row A, B are interconnected by cross bars 46 at definite intervals which may be varied in accordance with the height of the collecting receptacles 29, 30, 31. These cross bars serve as supports for the collecting receptacles 29, 30, 31, which for this purpose are provided each with four hooks 47 and will be lowered

when the chains are moved in the direction of the arrows (Figs. 4 and 5).

The cross bars or supports 46 are spaced in such a manner that a clearance approximately equal to the height of one collecting receptacle is formed between two superposed collecting receptacles. Further the receptacles in the different rows are arranged in a staggered manner in relation to one another.

For filling the matches contained in the boxes 13 into the collecting receptacles 29, 30, 31, in the illustrated example there are provided in correspondence with the two rows A, 15 B two tilting devices which may be alternately brought into and out of action. During their horizontal movement in the upper row the traveling boxes 13 are moved by means of their lugs 15 in suitable guides or slots 20 in the horizontal carriers 49, 50 of the tilting devices. These carriers are connected by means of bars 51, 52 to sleeves 53, 54 which are mounted free to turn on an axle 48. A sleeve 55 is loosely mounted on the 25 axle 48 and carries two toothed wheels 56 secured to it. The sleeve 55 carries projections 57, 58 which are adapted to engage corresponding notches in the sleeves 53, 54. For axially moving the sleeve 55 to and 30 from there is provided a double armed lever 59, 60 which is mounted to turn on an axle 61. The arm 59 of the lever engages a notch of the sleeve 55 between the toothed wheels 56. On the lever arm 60 there is 35 mounted a vertically movable pin 62 which is adapted to be pressed by a spring 63 into holes 64 in a plate 65 for the purpose of holding the sleeve 55 in position. The lever 59, 60 may either be turned by hand by 40 means of the handle 66, or automatically by the collecting receptacles 29, 30, 31. For this purpose the receptacles carry plates 67 which are adapted to move against lateral projections 69, 70 of the lever arm 60.

45 The sleeve 55 is caused to rock back and forth through 180° by means of a rack 68 engaging in the toothed wheels 56 on the sleeve. The rack 68 is horizontally reciprocated by means of a cam 71 on the main 50 shaft 9. The cam 71 acts on a roller carried by an arm 72 which is pivoted to the rack 68. By this means the tilting device with the traveling boxes either of the row A or B is caused to rock back and forth alternately from the position shown in full lines 55 in Fig. 5 in the direction of the arrow into the position shown in dot and dash lines in the same figure. The axis of rotation of the tilting device is preferably arranged near 60 the topmost layer of matches in the traveling boxes 13 whereby the paths of the matches in executing the rotary movement is made as small as possible.

The operation of the apparatus is as follows: The matches which are ejected from

the carrier bars 1 in the usual manner fall into the compartments of the traveling boxes 13. These compartments are filled thereby in one or more operations of ejection. The boxes 13 are now moved in the direction of the arrows in Figs. 1 and 3 by means of the wheels 18, 19 through a distance equal to the length of three boxes. This forward movement is interrupted when three fresh boxes to be emptied are inserted in one 75 of the tilting devices. In the position shown in Fig. 3 of the drawing the tilting device of the row B is in operation. By moving the rack 68 in Fig. 5 from left to right the traveling boxes 13 inserted into the tilting device of the row B are caused to be quickly tilted through 180 degrees into the position shown in dot and dash lines in Fig. 5, whereby the matches are discharged into the collecting receptacle 29 with their heads 80 lying toward the open outer side of the said receptacle. On moving the rack 68 in the opposite direction of the arrows (Figs. 4 and 5) for the purpose of rotating the traveling boxes inserted into the tilting device back into the position shown in full lines in Fig. 5, the wedge-shaped form of the walls 14 prevents the matches from being carried back out of the collecting receptacle and it also facilitates the lifting out 85 of the boxes from the pile of matches. When the boxes 13 have been thus returned into the position shown in full lines in Fig. 5 the horizontal pushing onward of the boxes in the manner above described recommences. Simultaneously the collecting receptacles 29, 90 30, 31 are moved downward by the chains 32—35 and the sequence of working is repeated. The speed of the intermittent downward motion of the collecting receptacles 95 may be adjusted at will, but is preferably made such that the wedge-shaped walls 14 of the traveling boxes 13 force themselves each time into the layer of matches contained 100 in the collecting receptacle. This arrangement has the effect of very quickly equalizing the difference of level of the uppermost layer of matches, and thus causing the matches to assume positions parallel to one another in passing along the partitions 105 110 of the boxes.

As Fig. 5 clearly shows the heads of the matches in the collecting receptacles are not touched by the tilting device. To still more secure the heads from being touched, the front walls of the wedge shaped partitions 14 may be cut off into a sloping form, as shown in Fig. 8.

The described procedure is repeated until the collecting box 29 is filled with matches. When this moment has arrived the plate 67 of the receptacle 30 moves downward against the projection 69 of the arm 60 whereby the sleeve 55 is disconnected from the sleeve 54 and connected to the sleeve 53. 115 120 125 130

By this means the tilting device of the row B is thrown out of action and the tilting device of the row A comes into operation. After the collecting box 30 is filled the tilting device of the row A is thrown out of action by the plate 67 of the receptacle 31 moving against the projection 70 of the arm 60, which the receptacle 31 has been lowered in the correct position in front of the tilting device of the row B and the second working period of the same begins.

The collecting receptacles after being filled may be removed by hand or by any suitable automatic means.

15 In the filling apparatus according to this invention the matches may be supplied uninterruptedly to the collecting receptacles, since after one receptacle of the first row has been filled the matches are allowed to 20 continue their travel until they reach the second row of collecting boxes, whereby time is gained for removing the full boxes and replacing the empty boxes in their position in the apparatus. By employing the apparatus 25 constructed in accordance with this invention it is possible to gain for the removal of the full collecting boxes and placing in position of the empty collecting boxes, at least such a span of time as corresponds to 30 that required for filling one collecting box with matches. This span of time only varies with the size of the collecting boxes to be filled which size depends on the ultimate purpose for which said collecting boxes are 35 to be used. The resulting advantage which the improved apparatus possesses over similar existing apparatus, consists in rendering unnecessary a stopping of the ejecting mechanism for the dip frames and of the mechanism 40 for feeding the matches to the collecting boxes.

The tilting device according to this invention has compared with other existing filling apparatus the advantage that the heads of 45 the matches are not liable to be jolted or pressed by the filling or discharging operation. Consequently for the purpose of discharging the matches, the matches need only be dried to such a degree as to avoid the 50 matches sticking together. A subsequent complete drying of the matches can take place in the improved apparatus owing to the fact that in being tilted, the matches may be turned through 180°, while their 55 heads are situated so as to point toward the axis of rotation, so that when they are in the collecting receptacle their heads will be situated so as to point outward. The improved apparatus has the further advantage that 60 the match heads cannot come in contact with metal parts. It has been found that the arrangement of the axis of rotation in or near the plane of the top layer of matches in the compartments produces the most favorable 65 conditions for tilting. Namely, the

matches can be tilted quickly without it being necessary to provide the cells with a cover or a front wall as was necessary in the tilting apparatus hitherto proposed. In the latter apparatus explosions were caused 70 by the removal of the cover.

I claim:

1. In an apparatus for discharging matches, collecting receptacles arranged in parallel rows, cells for conveying the matches, means for tilting the cells for discharging the matches into the collecting receptacles of the different rows, and means for moving said tilting means of the different rows alternately into the operative and 80 inoperative positions.

2. In an apparatus for discharging matches, collecting receptacles arranged in parallel rows, the collecting receptacles in the different rows being staggered in relation to one another and the superposed collecting receptacles in each row being separated from each other by a space approximately equal to the height of one collecting receptacle, cells for conveying the matches, 90 means for tilting the cells for discharging the matches into the collecting receptacles of the different rows, and means for moving said tilting means of the different rows alternately into the operative and 95 inoperative positions.

3. In an apparatus for discharging matches, a series of independent cells for conveying the matches, guides for said cells, match-feeding means discharging over said cells, means for intermittently moving the entire series of cells as a unit, pairs of parallel chains intermittently moved in a direction at right angles to the direction of movement of said cells, cross-bars connecting the chains in pairs, collecting receptacles for the matches supported on said bars and arranged in parallel rows, the receptacles in the different rows being staggered in relation to one another and the superposed collecting receptacles in each row being separated from each other by a space approximately equal to the height of one collecting receptacle, means for tilting the cells for discharging the matches into the collecting 110 receptacles of the different rows, and means for moving said tilting means of the different rows alternately into operative and 115 inoperative positions.

4. In an apparatus for discharging matches, a series of independent cells for conveying the matches, guides for said cells, match-feeding means discharging over said cells, means for intermittently moving the entire series of cells as a unit, pairs of parallel chains intermittently moved in a direction at right angles to the direction of movement of said cells, cross-bars connecting the chains in pairs, collecting receptacles for the matches supported on said bars and 120

125

130

arranged in parallel rows, the receptacles of the different rows being staggered in relation to one another, the superposed collecting receptacles in each row being separated from each other by a space approximately equal to the height of one collecting receptacle, means for tilting said cells for discharging the matches into the collecting receptacles of the different rows, a projection 10 on the bottom of each collecting receptacle continually moved in the same row, and means acted upon by the projections of the receptacles for moving said tilting means of the different rows alternately into 15 the operative and inoperative positions.

5. In an apparatus for discharging matches, cells for conveying the matches, and means for tilting the cells about an axis arranged near the topmost layer of 20 matches in the cells.

6. In an apparatus for discharging matches, cells for the matches, a tilting device for discharging the matches contained in said cells, and means for conveying said 25 cells into the tilting device, the axis of rotation of the tilting device being arranged

near the topmost layer of matches in the traveling boxes.

7. In an apparatus for discharging matches, collecting receptacles arranged in parallel rows, cells for conveying the matches, means for tilting the cells in a single operation through 180 degrees for discharging the matches into the collecting receptacles of the different rows, and means for moving said tilting means of the different rows alternately into operative and inoperative positions. 30 35

8. In an apparatus for discharging matches, cells for conveying the matches having wedge-shaped walls, collecting receptacles for the matches, means for tilting the cells and forcing the wedge-shaped cell walls into the layer of matches contained in 40 the collecting receptacles. 45

In testimony that I claim the foregoing as my invention, I have signed my name in presence of two subscribing witnesses.

HENRY ALFRED GSELL.
